DINSMORE AUSTIN, OF UNDERRILL, VERMONT, ASSIGNOR TO HIMSELF AND HOMER RAWSON.

Letters Patent No. 74,273, dated February 11, 1868.

IMPROVEMENT IN WHIFFLE-TREE.

The Schedule referred to in these Letters Patent and making part of the same.

TO ALL WHOM IT MAY CONCERN:

Be it known that I, DINSMORE AUSTIN, of Underhill, (assignor to myself and Homer Rawson, of Jericho,) in the county of Chittenden, and in the State of Vermont, have invented certain new and useful Improvements in Whiffle-Trees; and do hereby declare that the following is a full, clear, and exact description thereof, reference being had to the accompanying drawings, and the letters of reference marked thereon.

The annexed drawings, making a part of this specification, represent a horizontal section of a swingle-tree, which is made in two principal parts, the front part represented by A, and the back part by B. The front part, A, is made of wood, and has a cylindrical groove cut into and extending the entire length of its back side, into which are adjusted the spiral springs, c c, made fast at one end by the shoulder g, and is also bevelled toward the front, near the ends, and provided with the lip o, to fit into the groove o' of the back part, B. The back part of the swingle-tree, B, is ordinarily made of malleable iron, and enough longer than the part A that the flanges at each end, with which it is provided, may embrace, and the groove o' exactly fit over the lip o of the front part, A, and of such shape as to fit the back side of the front, A, to which it is screwed. It is also provided with slots, h and l. A pin or tug, a, is inserted through the hole in the end of the part B, which is made to correspond with the groove in the back side of the part A, until it reaches and presses on the end of the spring c, where it is kept from slipping out, and is worked backward and forward by the staple or loop e, driven into it, and which works in the slot h.

C represents a steel or other spring, attached to the back of the swingle-tree, by a clasp or staple, f, in which it slides, and is provided with a shoulder, x, at one end, and flange i at the other. The shoulder x passes through the part B, behind the coiled spring c, and works in the slot l, and the flange i clasps and securely holds the trace, b, against the end of the swingle-tree, and over the pin a.

The cord D, which is attached at one end to the pin a, by means of the loop or staple e, and run through the loop or pulley e', and thence to a carriage, or wherever desired, is designed to pull the pin a back or out of the trace b, by means of the staple e, working in the slot h, and the horse or other animal thereby detached from the carriage.

The steel spring C, which holds the trace b in place, by means of the flange i, may be pulled or sprung backward, or pulled out laterally, by means of the spring c, which rests against the shoulder x, so as to either slip the trace b over the pin a, or off of the same, and thereby attach to or detach the trace from the swingle-tree.

Having thus fully described my invention, what I claim as new, and desire to secure by Letters Patent, is—

1. The movable pin a, in combination with the spiral spring c, when used as and for the purpose specified.
2. The spring C, provided with a flange, i, and shoulder x, in combination with the spiral spring c, when used as and for the purpose set forth.

In testimony that I claim the foregoing, I have hereunto set my hand, this 5th day of December, 1867.

DINSMORE AUSTIN.
